UNITED STATES PATENT OFFICE.

PHILANDER E. LANE, OF ATLANTIC CITY, NEW JERSEY.

DROP-HAMMER.

1,337,520.

Specification of Letters Patent. Patented Apr. 20, 1920.

Application filed February 28, 1919. Serial No. 279,731.

To all whom it may concern:

Be it known that I, PHILANDER E. LANE, a citizen of the United States, residing at Atlantic City, in the county of Atlantic and State of New Jersey, have invented new and useful Improvements in Drop-Hammers, of which the following is a specification.

My present invention has to do with drop hammers, and pertains particularly to hammers of the friction lift type.

An object is to provide a drop hammer with the hammer carrying structure movably mounted on a crane, the device being thus adapted for use as a "persuader" or "dumper," upon a bending floor or in other connections where it is desirable to move the hammer to a proper operative relation with respect to the plate or other material being worked upon rather than shift the plate.

A further object resides in so constructing the friction lift and the release therefor that these parts will operate efficiently irrespective of the adjusted position to which the hammer is shifted.

A still further object is to construct the hammer proper so that when striking a plate, angle, or the like with a glancing blow the uneven strain of impact on the face of the hammer will be taken up within the hammer structure itself and undue strain will not be transmitted to the operating parts.

With these and other objects in view, which will be apparent from the specification, drawings, and claims, my present invention includes certain novel features of construction and combinations of parts which will now be set forth.

40 In the drawings:

Figure 1 is a view in side elevation illustrating the device of my invention as it is set up for use.

Fig. 2 is an enlarged view in end elevation of the device.

Fig. 3 is a view in side elevation of the disclosure in Fig. 2.

Fig. 4 is a fragmentary sectional view to better illustrate the crane car by which the hammer proper is carried.

Fig. 5 is a detail view illustrating the compensating cushion within the hammer.

In the present illustration I have shown my invention embodied with a jib crane, it being however understood that the inven-

tion is adaptable for use with other forms of crane or support.

The pivot pillar of the jib crane is shown at 1, this pivot pillar being journaled in bearings 2 and 3 which are mounted on any suitable supporting structure. The jib beam 4 is secured to extend radially from the pivot pillar 1, and brace rods 5 are provided to maintain beam 4 in true horizontal disposition and against sliding.

65 Jib beam 4 is a section of I-beam or is made up of other suitable material, and a car consisting of side plates 5 and 6 connected by axles 7 and by wheels 8 and 9 journaled on these axles, is mounted to have 70 traveling movement on said beam. An electric or fluid motor 10, or other suitable power means, is mounted on the inner end of beam 4 adjacent pivot pillar 1, and the remaining portion of this beam is clear for 75 travel of the car.

A pinion 11 mounted on the motor shaft meshes to drive a larger spur wheel 12 fixed on shaft 13. This shaft 13 is journaled at one end adjacent motor 10, and extends parallel with and above beam 4, the outer end being journaled in a bearing provided on standard 14. Shaft 13 has a key-way 15 formed throughout the greater part of the length thereof inside of standard 14, and a 80 friction roll 16 has a key 17 received to slide in key-way 15. Plate 6 has bearing extensions 17' which are received upon shaft 13 on opposite sides of friction roll 16, and thus as the car is moved along beam 4 roll 90 16 is carried therewith. In this movement of 16 the key 17 slides in key-way 15, and thus this roll is fixed to turn with shaft 13.

A pair of bearing extensions 18 carried by plate 5 have an idler roll 19 journaled therein, and a second pair of bearings 20 mount a bearing roll 21 to be spaced slightly from roll 19. A set of bearing extensions 22 is carried by plate 6 somewhat spaced from bearing extensions 17', and a pressure roll 100 23 is journaled therein. This pressure roll is mounted to be adjustable in its disposition with respect to friction roll 16, and the adjustment is accomplished through a lever 24, a cable or rod 25 being attached for manipulation of this lever from a distance.

It is preferable that plates 5 and 6 extend somewhat below the lower edge of beam 4, and rollers 26 are carried by these plates to guard against upward movement and 110

displacement of the car. Slide bearings 27 and 28 are provided on the lower extensions of plates 5 and 6 and are lined up vertically beneath the space between the rolls 19 and 21, and 16 and 23 respectively. A cross-head 29 has friction boards or bars 30 and 31 rigidly connected therewith and extending in parallel spaced relation, this spacing being sufficient to center up with slide bearings 27 and 28 and boards or bars 30 and 31 are shaped to slide freely within the bearings, these bearings guiding the boards or bars to be received between the sets of rolls.

10 A driving head or hammer block 32 is mounted from crosshead 29 by a king bolt 33, this head or block being somewhat separated from the crosshead, and rubber cushions or compensating springs 34 are mounted between crosshead 29 and the head or block 32, and as king bolt 33 is loosely received through crosshead 29, movement of head or block 32 within the limits of resiliency of the rubber cushions or springs is allowed. This construction of cushioned 15 head relieves some strain upon the parts due to the shock of impact as the hammer drops, compensates for a glancing blow due to the impact face of head or block 32 striking an angular or rounded surface, and causes a 20 rebound of the hammer structure which will aid in the successive lift of the hammer.

In the use of the device, the parts are assembled and mounted substantially as shown in Fig. 1, and as has been stated this 25 mounting is adjacent a bending slab floor or other surface on which metal plates, shapes, or the like are to be worked. The jib beam 4 is swung to be alined vertically over the material to be worked on, and the 30 car is then moved along this beam to bring the hammer structure over the particular point at which blows are to be struck. The motor 10 is started and by manipulation of cable or rod 25, operating lever 24 is shifted 35 to throw pressure roller 23 into bearing contact with board or bar 6. As roll 23 bears against this board or bar, it is forced against friction roll 16, and as this roll is constantly revolving force is exerted to raise the hammer. 40 When the hammer has been lifted to the proper height, proportioned by the force desired in the hammer blow, operating lever 24 is shifted in an opposite direction and the hammer is released to drop. As the several bearing extensions by which the rolls 45 are mounted are carried with the car structure, these parts will be maintained in proper relation irrespective of the location

of the car structure along beam 4, and as key 17 slides in key way 15 roll 16 is constantly 50 revolved when motor 10 is in operation.

While, in the foregoing, I have described specific embodiments, and have mentioned only certain possible modifications, it will be appreciated that my purpose is to provide a drop hammer structure in which the hammer is carried by a jib or other crane to be adjustable, in view of which it is to be understood that in practice I do not limit myself to such specific details as herein set 65 forth, but may resort to any practical modifications falling within the scope of the invention as defined in the appended claims.

I claim:

1. A drop hammer including with a crane 75 having a swinging beam, a car mounted for movement along said beam, a friction lift hammer having friction bars associated therewith carried by said car, power means fixed on said beam adjacent the inner end thereof, a shaft journaled on said beam and extending parallel therewith throughout its length, said shaft being driven by said power means and having a key-way extending longitudinally of the greater part of 80 the length thereof, a friction roll bearing against one of said friction bars and by which said hammer is lifted slidably mounted on said shaft and having a key sliding in said key-way, and bearing extensions by 85 which said roll is moved when said car is moved.

2. A drop hammer including with a jib 90 crane structure, a car mounted to travel over the outer extent of the beam of said crane, power means mounted on said beam at the inner end thereof, a shaft driven by said power means journaled above and parallel with said beam, said shaft having a key-way 95 formed longitudinally of the outer extent thereof and extending for length corresponding to the distance of travel of said car, a friction lift hammer structure held in operative position on said car by suitable slides and rolls, a friction roll slidably 100 mounted on said shaft and having a key received in the key-way thereof, extensions carried by said car to move said friction roll as the car is moved and to maintain the same at all times in an operative position, and a 105 pressure roll mounted adjacent said friction roll and shiftable to render the parts operative and inoperative.

In testimony whereof I affix my signature.

PHILANDER E. LANE.
